UNITED STATES PATENT OFFICE.

MATTHIAS BROCK, OF BOSTON, MASSACHUSETTS, ASSIGNOR TO UNITED SHOE MACHINERY COMPANY, OF PATERSON, NEW JERSEY, A CORPORATION OF NEW JERSEY.

MACHINE FOR MOUNTING SHOES.

1,065,583.

Specification of Letters Patent. Patented June 24, 1913.

Application filed December 13, 1910. Serial No. 597,055.

To all whom it may concern.:

Be it known that I, MATTHIAS BROCK, a citizen of the United States, residing at Boston, in the county of Suffolk and State 5 of Massachusetts, have invented certain Improvements in Machines for Mounting Shoes, of which the following description, in connection with the accompanying drawings, is a specification, like reference characters on the drawings indicating like parts 10 in the several figures.

This invention relates to machines for use in the manufacture of boots and shoes and particularly to machines for mounting partially made shoes on the lasts upon which the manufacture of the shoes is to be continued.

While the machine in which the invention is herein shown as embodied for illustrative 20 purposes is designed particularly for mounting stitch down shoes upon their lasts certain of the features of this invention are of general application to lasting and other machines for dealing with various kinds of 25 shoes.

In the method of manufacturing stitch down shoes in which this machine has been used the shoe upper materials and the inner-sole or sock lining are connected together 30 by means of an inseam without a last in the shoe. Thereafter the shoe is mounted upon its last and the outersole is attached and the other making operations continued. While it is customary to mold or shape the toe and 35 heel portions of the shoe upper to a greater or less extent as a preparatory operation before the upper is connected to the sole, the first stretching and conforming of the shoe to its last is effected in the operation of 40 mounting the shoe upon the last. It is obvious that in order that the shoe shall be substantially stretched and conformed to its last the last must be large enough to fill and distend the shoe to some extent. These conditions make the operation of mounting the 45 shoe on its last a difficult and laborious one as that operation has heretofore been carried on by hand.

One of the objects of this invention is to 50 provide a machine by which the laborious part of this operation shall be done largely by power and by which shoes can be stretched over lasts that are somewhat larger than it has been practical to mount the shoes

on by hand. This enables the shoe to be 55 stretched more and thereby conformed to its last to a greater extent than has heretofore been possible.

Another advantage resulting from the use of this machine is that the shoes are mounted with much less liability of tearing, ripping or otherwise injuring them than occurs when the work is done by hand. As I am advised, this is the first machine to have been devised for doing this work.

Broad features of the invention are to be 65 recognized in the general organization of the machine.

One important feature of the invention consists in means for engaging a shoe at 70 the toe end and forcing it upon the last. In the illustrated machine the last is fixedly supported and the toe engaging means is actuated but obviously the last might be the part to be moved. In the illustrated machine a member of the toe engaging means 75 comprises plates which may be essentially like the toe lasting plates or wipers commonly employed in bed lasting machines. The toe engaging plates of this present machine are formed in pairs with abutting or 80 pivotally connected adjacent ends and a concaved shoe engaging edge shaped to correspond substantially with the contour of the edge of the last bottom and these plates are 85 mounted for advancing and relative closing movement inwardly over the edge of the last from the end and sides of the toe. In the illustrated use of these plates, they advance 90 and close to shape the upper to the edge of 90 the last and crease it slightly in over the last bottom to form the welt crease or the crease in a stitch down shoe which corresponds substantially to the welt crease of a 95 welt shoe. While the upper is preferably 100 creased initially in the preparatory toe molding operation, this crease loses its shape more or less during the intervening steps and it is important that it be restored and, if need be, perfected in the operation of this 105 machine which it will be understood is the real lasting operation in the manufacture of stitch down shoes.

A very important feature of this invention relating to these lasting plates is that 105 they are mounted for reversal. As is well understood, by those familiar with shoe lasting, the contours of the toe ends of right

and left shoes are not alike but in certain respects are the reverse, one of the other. Because of this fact separate sets of wipers have to be provided for left and for right shoes. By forming reversible wipers, however, the same wipers may be used one side up for right shoes and the reverse side up for left shoes. I am aware that it has been proposed to use a one piece U-shaped plate 10 which is reversible.

As distinguished from that proposed construction, my invention comprises co-acting wipers adapted for wiping the upper over the toe of the last and a support for said 15 wipers, said wipers being reversible whereby they are adapted to operate on a right or a left last by turning them upside down. It is to be understood that the lasting plates or wipers herein shown as embodying this 20 feature of the invention are adapted for use in bed lasting machines and that this feature of the invention is not limited to the particular wipers shown but may be applied to end lasting wipers generally.

25 A special feature herein employed of the above described invention and one which is of substantial advantage is that the wipers, together with their holder, in which they have their operative movements, is mounted to turn upon an axis extending longitudinally of the shoe and located substantially midway between the planes of the upper and lower faces of the wipers for effecting reversal of the wipers for right and left 30 shoes.

An advantage of this invention is that by its use the wipers can be reversed without detaching each wiper from its carrier or holder and applying it in the place of the 40 other wiper. In a commercial type of bed lasting machine the wipers and their holder are movable through a small angle for the purpose of adjustment about an axis extending longitudinally of the shoe and located 45 substantially in the plane of the lower face of the wipers. This arrangement permits adjustment of the wipers into parallelism with last bottoms which are inclined transversely.

50 The present invention will be recognized as distinguished from the known construction in that a complete reversal or overturning of the wipers is provided for as distinguished from a limited adjustment 55 which did not accomplish the present object. In the form in which this feature of the invention is illustrated the wiper holder has a stem removable with the holder and the wipers from the wiper support. After 60 having been so removed the wiper and holders can be overturned and the parts replaced with the wipers adapted for the mate of the shoe upon which they were last used.

The wiper support has a shelf or formed 65 face with which a face of the wiper holder

co-acts to prevent or limit rotation of the holder and wipers when the parts are in operative relation. Obviously it is not essential to withdraw the stem of the wiper holder entirely from its support but it may be withdrawn only far enough to allow the holder to clear the shelf after which the holder may be rotated and then the parts forced back into operative position in which the shelf holds them against rotation. The 70 toe lasting plates may advantageously be arranged for use in the special machine herein shown for automatic opening and closing movement and they are herein shown as yieldingly maintained in their closed position and adapted to be opened more or less against suitably stiff springs by their engagement with the shoe. Conveniently they are moved longitudinally of the shoe and the latter wedges them apart to the 80 width required for the particular shoe after which engagement of the toe end of the shoe with the adjacent portions of the wipers produces a balanced relation of the plates and enables them to exert substantially uniform overwiping pressure throughout the length of their shoe engaging edges. 85

The toe engaging means preferably comprises, in addition to the lasting plates above mentioned which engage the shoe in 90 the welt crease, a member for engaging the shoe bottom and pressing rearwardly, and in the combination of these two engaging means in a shoe mounting machine is found another broad feature of this invention. 95 The shoe bottom engaging member may conveniently comprise a block which is positioned lengthwise of the shoe with the toe lasting plates when the latter are brought into operative relation to the shoe. For 100 convenience in positioning the wiper plates about the shoe, said block will preferably be arranged to swing downwardly by a special movement from an out-of-the-way position. Means is provided for clamping the block 105 against the shoe bottom and the downward swinging movement will conveniently be effected by the same manipulation of a hand lever which produces the clamping. The clamping block is connected to the support by which the lasting plates are moved forwardly whereby the block and the plates co-operate for forcing the shoe rearwardly on to the last. This movement of the above 110 mentioned parts is effected by power driven 115 mechanism.

In accordance with an advantageous feature of this invention, provision is made for a slight relative movement of the lasting plates and the shoe bottom engaging block 120 longitudinally. This arrangement is caused to effect a backward movement of the shoe bottom or innersole relatively to the wipers and serves to draw upwardly and backwardly over the toe end of the last the in- 125 130

seam and adjacent portions of the shoe stock with which special difficulty is experienced in manipulating them to proper position over the last. For the above described purpose the wiper holder is arranged to have a limited movement backwardly in the wiper support against a spring during the first part of the forward actuation of said support.

- 10 In the illustrated embodiment of the invention the last is fixedly supported by a post having a pin to enter the usual last pin hole. The above described devices are yieldingly actuated by power mechanism toward 70 the heel of the shoe. This actuating mechanism comprises a slide which has a uniform stroke at each operation of the machine and upon which the wiper support is adapted for movement longitudinally of the machine 75 20 to position the wipers relatively to a shoe of any length that is to be operated upon.

A feature of this invention is that the said support is automatically clamped to the slide in whatever position it is initially 80 adjusted. In the preferred embodiment of this feature the clamping is effected by an eccentric which will be manipulated into clamping position without special attention from the operator. To this end, as here 85 shown, the eccentric is connected to the means by which the shoe bottom engaging member is actuated. This provides that the support shall be free for movement while the wipers are being positioned and that 90 when the said engaging member is clamped down upon the shoe the eccentric will be automatically set to cause the shoe mounting devices to be actuated when the power is applied by the usual treadle controlled 95 40 clutch. As above indicated, the support which carries said devices is yieldingly actuated and, in order to avoid liability of producing too severe action of the shoe engaging devices provision is made for automatically disconnecting the support from the slide after a predetermined compression of the spring through which the slide is actuated. For this purpose the eccentric is provided with an operating stud that stands 100 45 in the path of an adjustable stop with which it engages after compression of the spring to turn it out of clamping relation to the slide. In accordance with a further feature 105 of this invention, this adjustable stop may 50 be arranged always to disengage the eccentric from the slide at or before the end of the advance stroke of the devices engaging the forepart of the shoe whereby said devices shall not in the return stroke do damage to the shoe. In the preferred arrangement, the connection of the eccentric with the shoe bottom clamp effects the lifting of the clamp from the shoe when the eccentric 110 55 is unlocked from the slide and during the 60 back stroke of the slide the eccentric and 65

other members engage the slide with sufficient friction to draw the wiper and clamp support away from the shoe so that at the end of the operation the shoe is free from said devices and ready to be removed from 70 the machine.

A further feature of this invention is found in novel mechanism for drawing the heel portion of a shoe over the heel of a last and a still further feature in the combination of devices working at the heel with devices operating at the toe of a shoe for movement in predetermined time relation to mount the shoe upon its last.

The shoe mounting means located at the heel comprise a spoon or horn of suitable shape to enter the shoe between the counter and the heel end of the last and draw the shoe downwardly over the last. This spoon, as it will be called, is herein shown as arranged to have an operative stroke substantially longer than the height of the last when used for mounting stitch down shoes the heel portions of which have no inner soles or turn shoes in which the heel portion of the sole is not connected to the upper before the shoe is mounted or remounted upon its last. This permits the spoon to be projected upwardly through the bottom of the shoe and to be drawn in frictional contact with the shoe through a longer distance than would otherwise be permitted. The spoon is connected to the power mechanism and timed to begin its operation after the initial movement of the forepart engaging devices. In one construction, the spoon is arranged for actuation yieldingly in the direction to uplift it or return it to starting position in order that if high shoes are to be worked upon in which the downward stroke of the spoon does not free it entirely from the shoe leg, there will not be liability that in its return stroke it will dislodge the shoe from the last.

These and other features of the invention 110 will more fully appear in connection with the following description of the illustrated machine and will then be pointed out in the claims.

Figure 1 is a side elevation of a preferred 115 embodiment of the machine; Fig. 2 is a detail, partly in section, of the spoon mechanism; Fig. 3 is an elevation of the toe end of the machine; Fig. 4 is a perspective view of a shoe and the several shoe engaging devices at the end of the advance stroke of the operating mechanism; Fig. 5 shows the devices diagrammatically; Fig. 6 is a perspective view of the toe lasting plates; Fig. 7 is a perspective view in section of the 120 clutch mechanism; Fig. 8 is a side elevation embodying, as to some features, a modified construction.

The operating mechanism is carried by a pedestal or frame 2, in one upwardly rising 125

branch 4 of which is arranged a last support 5 the front face of which is formed with ratchet teeth to permit the support 5 to be secured in vertically adjusted position 5 by a ratchet block 6. The division between the arm 4 and the body of the post permits the application of a long-legged boot to the support. In the top of the front arm or body of the frame 2 is formed a horizontal 10 guideway having a slide 10. In this slide is a second guideway in which moves the intermediate slide 12 over which is mounted the foot 14 of the support 15. The foot 14 has lateral guide ribs as shown in the end 15 elevation, Fig. 3, arranged to move in ways in the frame 2 and rest upon the slide 10. There is a spring 16 arranged between an upstanding lug 17 on the intermediate slide and a lug 18 depending from the support. 20 This spring transmits movement of the intermediate slide 12 yieldingly to the support. The support 15 has a socket in which is vertically adjustable a post 20 carrying a head 22. This head has a cylindrical 25 socket opening outwardly toward the last support and having a reduced opposite end. In this socket is received the stem 25 of the lasting plate holder which latter is shown most clearly in Fig. 6. The stem of the 30 holder is cylindrical while the holder itself has flat upper and lower faces in alignment with the sides of the stem. The head 22 has a shelf 23 upon which the flat face of the holder rests when the stem is in its 35 socket, thus preventing or limiting angular movement of the holder. A spring pressed pin 26 rising from the shelf extends into a shallow groove 27 in the stem and retains said parts normally in the head 22. The 40 stem has a recess in which is received a spring 28 which abuts against an adjustable stop 30. This spring 28 and the slot 27 permit the lasting plates and their holder to yield toward the head 22 during the operation 45 of the machine and the spring 28 returns the lasting plates to their normal forwardly projecting position.

Referring to Figs. 4 and 6, the holder comprises a body portion which may be 50 integral with the stem 25 and a cover plate 32. Between these members is formed a recess to receive the lasting plate carriers or cams 35 to which the lasting plates 36 are attached. These lasting plates are or may 55 be substantially like the lasting plates used in the commercial bed lasting machines and comprise two members having abutting adjacent ends and presenting together a concave working edge shaped to embrace the 60 toe portion of a shoe and to advance and close over the shoe bottom into a position for laying the upper evenly over the marginal portion of a shoe bottom. The rear side walls of the recess, in which said plates 65 and their cams move, are curved about a

center which is substantially the point of contact of the acting edges of the wiper plates. The cams 35 are provided with curved slots in which stand studs rising from the holder. A spring 38 is arranged between the rear faces of the two cams and holds those ends normally apart thus maintaining the wiper plates 36 normally in their closed position and permitting them to be forced apart by wedging a stitch 70 down shoe between them with the wiper plates in the welt crease. This is one form of automatically operating toe wipers which has been found satisfactory but obviously other forms of toe lasting wipers may be 75 substituted which may be automatic or non-automatic, as, for example, the usually manually operated toe wipers of the commercial bed lasting machines. The wiper plates are shown as having like bevels upon their upper and their lower faces and are mounted with said upper and lower faces symmetrical with relation to the axis of the stem 25. The acting edges of the wiper plates are shaped as above suggested in accordance with the contour of the toe portion of the shoe which they are to embrace. As is well understood, the contour of the toe portion of a right shoe differs materially from the contour of the toe portion of its mate, 90 that is the toe portion of a left shoe, and is, so far as these differences are concerned, 95 the reverse of its mate.

With the arrangement above described for mounting the lasting plates, they can be 100 used as shown for a right shoe and when a left shoe is to be operated upon the stem 25 may be partially withdrawn from the head 22 to clear the holder from its shelf 23 and then turned through a half-revolution to 105 present the lasting plates in position for working upon a left shoe. When the holder and its stem are forced backwardly again into their seat the shelf 23 and the spring pin 26 hold these parts in their reversed position. The head 22 pivotally supports at 110 its other end a lever 40 between the rear end of which and a rearwardly projecting arm of the head is a toggle comprising the members 42, 43 of which the latter is extended upwardly to form a handle 44. On the opposite end of the lever 40 is mounted the shoe bottom engaging member 45 which is shaped to present a broad toothed bearing against the shoe bottom, that is to say, 115 against the innersole or sock lining of the stitch down shoe adjacent to the stem which connects the insole to the upper, and to present a separate toothed face for engaging the innersole over the ball of the last. This 120 engaging member is pivoted upon the lever 40 and has an upwardly extending arm which is slotted to receive a pin on a forwardly extending arm 21 of the head 22. By reason of this connection the member 45 125 130

- is tipped about its pivotal connection with the lever 40 when said member is raised, whereby the member is turned upwardly out of the way to facilitate positioning of the 5 shoe and the lasting plates relatively. The support 15 may conveniently have a laterally projecting handle 48 by means of which it may be slipped forwardly and backwardly.
- 10 The support 15 is normally free to move on the intermediate slide 12 to permit it to be freely adjusted for presenting the lasting plates 36 to the size of shoe that is on the last post 5 and after the lasting plates have 15 been positioned for operation the support is locked to said slide. This locking is effected by an eccentric 50 that is pivoted to an ear 52 that is pivotally connected to a support 15 and engages the intermediate slide 12.
- 20 For operating this eccentric it is connected with a link 53 and a depending arm of the toggle member 42. By reason of this connection the eccentric is set to lock the support and its actuating mechanism by the manual 25 manipulation that is employed for throwing the insole engaging member into its operative position. The power actuation of these parts is effected by a connection through a link 60 from a depending portion of the 30 slide 10 to an eccentric stud 61 on a disk 62. This disk which is formed on the stub shaft 63 is toothed and is driven by a pinion 64 on the main shaft 65 which carries a pulley wheel 66. The shaft is connected to the 35 pulley wheel by a one revolution clutch, shown in Fig. 7, and comprises a sliding pin 67 adapted to be withdrawn from engagement with a notched pulley disk 68 by a wedge 69. The wedge 69 is carried by a 40 lever 70, Fig. 1, pivoted to the frame at 72 and having a steel block 73 riding on a clutch controlling cam 74 fast on the stub shaft 63. When the block 73 drops into the 45 low portion of the cam 74 the wedge is lowered into the path of the clutch pin 67. The clutch lever 70 is connected by a rod 76 to an operating treadle 75, Fig. 8, which is uplifted by a spring 78. This spring serves to hold the clutch lever down upon its cam 74.
- 50 The described arrangement in which the controlling cam 74 is on the same shaft as the disk 62 which carries the stud 61 for actuating the parts provides that the machine shall run uninterruptedly through a cycle 55 and stop at the end thereof. In order to avoid damage to a shoe which might result from continuance of the operation by the driving mechanism the eccentric 50 may be released from the driving mechanism at any 60 time by the operation of the lever 44. The spring 16 is designed to prevent excessive straining of the shoe but provision is also made for use, if desired, to limit the forward stroke of the devices which engage the toe 65 portion of the shoe. This is in the form of an adjustable wedge 80 arranged in the path of a stud 82 on the eccentric 50 to disengage said eccentric automatically from the operating mechanism at a selected point in this forward stroke. The stud 82, after riding down the wedge in the back stroke, allows the eccentric to engage the slide 12 with sufficient friction, in addition to the other friction between the moving parts, to cause the support 15 and its associated devices to be 70 carried away from the shoe in the backward stroke of the actuating mechanism. The link 60 connected to the driving mechanism also operates a lever 85 which is pivoted to the frame at 72 and to a link 86 which operates a bell crank 88. The bell crank is in turn connected by a link to a vertical slide 89 which is connected with a spoon carrier 90 to the upper end of which the spoon 91 is pivoted. This spoon comprises thin spring 80 steel blades shaped to extend between the rear end face of the last and the adjacent face of the heel portion of a shoe to guide and pull the shoe down over the last. The lever 85 may have a pin and slot or lost motion connection with the link 86, as shown in dotted lines in Fig. 1, and a spring 92 is arranged to move said link and the spoon 85 yieldingly upwardly. This arrangement gives positive downward movement of the 90 spoon and yielding return movement so that if the spoon is not entirely withdrawn from the shoe during its downward movement, as may happen with a long legged boot, it will not be forced upwardly and be liable to lift the shoe from the last. Preferably the spoon will be formed to spring automatically away from the shoe as soon as it has been withdrawn from between the shoe and the last whereby it will normally rise outside of 95 the shoe in its return stroke.
- In Fig. 2 a modification is shown in which the spoon carrier 90 is connected to the slide 89 by a pin and slot and a spring 93 connected to the frame and to said spoon carrier effects yieldingly the uplift of the spoon during the return stroke of the driven parts.
- In Fig. 8 is shown a modified form of the devices which engage the forepart of the 115 shoe. In this construction the post 20 is replaced by a post 120 which has forwardly and backwardly extended shelves 121 and a bifurcated upper end upon which is pivotally connected the head 122. Adjusting 120 screws fix the head in angular position relatively to the post and the plane of the shoe bottom for operating upon shoes of different shapes. In this construction the stem of the lasting plate holder is provided with an 125 annular groove engaged by a spring pressed plunger 123 to retain the stem yieldingly in the head but permit it to be drawn outwardly for reversing the lasting plates. The lasting plate holder rests upon one of the 130

3
 adjusting screws, above mentioned, to restrain it from loose tipping movement. The shoe bottom engaging member 45 is an eccentric faced toothed block pivoted to the head 122 and actuated by its own lever 146 there being a stop 147 to hold the lever against loose movement during the operation of the machine. The eccentric block 50 is in this instance connected by a link 153 to a bell crank pivoted on the head 122 and one arm 144 of which is formed as a handle for manually operating the eccentric. The head has, in this case, an upright handle 148 by means of which the entire mechanism 5 operating the toe of the shoe can be slid forwardly upon the intermediate slide 12.

In the operation of the machine the workman will place on the spindle 5 a last which has been partially inserted in a shoe but the last may be applied naked and the forepart of the shoe thrust upon it after the last is in position in the machine. The support 15 will then be drawn forwardly by the handle 48 to bring the lasting plates 36 into operative relation to the shoe. Upon this movement the lasting plates engage the shoe in the welt crease and are wedged apart until brought into firm engagement with the shoe throughout the length of their acting edges. This position is shown in Fig. 5. The bottom engaging member 45 will then be turned downwardly and pressed against the shoe where it will be retained by the straightening of the toggle members 42, 43. In applying the shoe the spoon will be inserted between the heel portion of the shoe and the heel end face of the last, as shown in Fig. 5. At the same time that the toggle members are straightened the eccentric 50 is turned to lock the support 15 to the power actuated mechanism. The operator next depresses the treadle 75 to close the clutch and having his hands entirely free, he may, in accordance with the requirements of the work and his skill, assist in manipulating the shoe to cause it to be mounted upon the last, that is, to have the forepart forced rearwardly upon the last until it fits the last snugly and is properly arranged on the last 50 to have the heel part of the shoe drawn downwardly over the heel part of the last. In the power operation the spring 28, Fig. 1, permits the lasting plates to yield backwardly to a slight extent while the bottom engaging member 45 is unyieldingly forced ahead. By these relative movements the innersole is tightened rearwardly and caused to draw the toe end of the shoe upwardly toward the plane of the last bottom, see Fig. 5. The spring 16 is compressed during the advance stroke of the actuating mechanism so that the devices engaging the forepart of the shoe are acted upon by a gradually increasing yielding pressure to do their work. 60 If the wedge block 80 is set for that purpose,

as it preferably will be, it will disengage the eccentric upon the slide 12 before the end of the advance stroke of the actuating mechanism. This disengagement effects a breaking of the toggle members 42, 43 and a consequent lifting or release of the bottom engaging member 45 from the shoe so that in the return stroke said member does not drag objectionably over the shoe bottom. The support 15 and the several members carried by it are then moved away from the shoe by frictional engagement with the intermediate slide 12. During the forward stroke the spoon has been drawn downwardly to pull the heel portion of the shoe down over the heel portion of the last and preferably is withdrawn from the shoe and permitted to spring outwardly away therefrom so that in the return stroke it will not reengage the shoe. When the limit of the return stroke is reached the clutch is automatically opened by the action of the wedge 69 and the machine comes to rest. If the next shoe to be lasted is the mate to the one just operated upon the lasting plate holder will be pulled forwardly until the stem 25 can be turned in the head 22 whereby the holder will be moved through a half revolution for reversing the wipers and presenting them upside down in which position they will fit the mate of the shoe first operated upon. Return of the holder and its stem to original position locks the holder against loose movement, although preferably permitting the slight amount of tipping which may be required for fitting differently shaped shoes as is well understood by those familiar with the operation of bed lasting machines.

Having explained the nature of this invention, described a preferred construction embodying the same and explained how the invention may be used, I desire to secure by Letters Patent of the United States protection for all of the patentable novelty herein disclosed and with this intent, make the following claims:

1. A shoe mounting machine having, in combination, means for supporting a last, means shaped and arranged to engage a shoe in the welt crease around the toe, means for actuating the engaging means to force the shoe on to the last and other means engaging a different part of the shoe and actuated in a direction to coöperate with the first-mentioned means to force the shoe heelward on the last.
2. A shoe mounting machine having, in combination, means for supporting a last, means shaped and arranged to engage a shoe in the welt crease around the toe, coöperating means engaging a different portion of the shoe and power driven means to actuate said engaging means and the last relatively lengthwise of the last to force the shoe on to the last.

3. A shoe mounting machine having, in combination, means for supporting a last, means shaped and arranged to engage a shoe in the welt crease around the toe, means for engaging the shoe bottom over the forepart of the last, and means for actuating said two engaging means and the last relatively to force the shoe rearwardly on to the last.
4. A shoe mounting machine having, in combination, means presenting a concave acting edge to engage a shoe in the welt crease around the toe, means for engaging the shoe bottom over the toe, and means by which said first engaging means may be actuated with the second engaging means.
5. A shoe mounting machine having, in combination, means presenting a concave acting edge to engage a shoe in the welt crease around the toe, and power actuating mechanism having a predetermined stroke and arranged to impart a variable movement to said engaging means lengthwise of a partially inserted last to force the shoe on to the last.
6. A shoe mounting machine having, in combination, means presenting a concave acting face to engage a shoe in the welt crease around the toe, a shoe bottom engaging member, and a support common to both said engaging means and on which one of said engaging means is movable relatively to the other lengthwise of the shoe to accelerate the movement of the shoe bottom over the last.
7. A shoe mounting machine having, in combination, lasting plates having concave edges to embrace the toe portion of a shoe, a shoe bottom engaging member constructed and arranged to grip the insole, a support in which the lasting plates are yieldingly mounted and the insole gripper is yieldingly mounted, and means for moving said support longitudinally of the last, for the purpose described.
8. A shoe mounting machine having, in combination, lasting plates having concave edges to embrace the toe portion of a stitch down shoe in the welt crease for forcing it over a last and shaping it, a support for said plates, a support for a last partially inserted into the shoe, and power mechanism for yieldingly actuating said two supports relatively lengthwise of the shoe, for the purpose described.
9. A shoe mounting machine having, in combination, lasting plates having concave edges to embrace the toe portion of a stitch down shoe in the welt crease, a coöperating member having backwardly faced teeth to engage the insole of the shoe over the toe, means whereby said members may be actuated to engage the work, and means whereby they may be operated to force the shoe on to the last.
10. A machine of the class described having, in combination, lasting plates abutted together and presenting a substantially continuous acting edge shaped to embrace the toe of a shoe in the welt crease, holding and guiding means for said lasting plates, means for yieldingly holding them normally closed together and permitting them to be wedged open as they are pressed rearwardly against the shoe, and means whereby said plates may be operated to force a shoe on to a last which has been partially inserted into the shoe and to shape the toe portion of the shoe in the welt crease to that last.
11. A machine of the class described having, in combination, lasting plates abutted together and presenting a substantially continuous acting edge shaped to embrace the toe of a shoe in the welt crease, holding and guiding means for said lasting plates, means for yieldingly holding them normally closed together and permitting them to be wedged open as they are pressed rearwardly against the shoe, a last support and power driven means by which said lasting plates and support may be yieldingly actuated for forcing the toe portion of a shoe on to the last and shaping that portion of the shoe to the last.
12. A machine of the class described having, in combination, lasting plates, a holder in which the plates are mounted for operation, and a support in which the holder is rotatable to reverse the plates whereby they may be presented with either face uppermost.
13. A machine of the class described having, in combination, lasting plates, a holder in which the plates are mounted for operation, a support relatively to which the holder is arranged for semi-rotation about an axis extending longitudinally of the shoe, and means for retaining the holder in adjusted position with the wipers either side uppermost.
14. A machine of the class described having, in combination, toe lasting plates, a holder in which the plates are mounted for operation and a support in which the holder is arranged to be displaced longitudinally of the shoe and then given a half-revolution for reversing the toe lasting plates, said support and holder having coöperating devices for restraining the holder from rotation when it is in its normal position.
15. A machine of the class described having, in combination, lasting plates, a holder having a stem the axis of which is in a plane substantially midway between the upper and lower faces of the lasting plates, and a support in which the holder is arranged to be given a half-revolution about said axis for reversing the lasting plates.
16. A machine of the class described having, in combination, lasting plates, a holder in which the plates are mounted for opera-

- tion and a support having a recess to receive the stem and a shelf to underlie the holder, said parts being arranged to permit partial withdrawal of the stem from the support to cause the holder to clear the shelf and for semi-rotation of the holder to reverse the wipers while the parts are in this relation, said shelf restraining rotation of the holder while the stem is fully in the support. 5
17. A machine of the class described having, in combination, a shoe support and a shoe bottom engaging member, a lever upon which said member is mounted to apply pressure to the shoe and a connection between said member and a relatively stationary part of the machine for swinging said member toward operative relation to the plane of the shoe bottom by movement of the lever in the direction for applying pressure and for reversely swinging said block during movement of the lever in the direction to release pressure. 10
18. A machine of the class described having, in combination, lasting plates comprising co-acting members for wiping the upper over the toe portion of a last, a support for said lasting plates, said support being reversible whereby the wipers are adapted to operate upon a right or a left last by turning their support upside down. 15
19. A shoe mounting machine having, in combination, means to engage the toe of the shoe in the welt crease, means to engage between the heel end face of a partially inserted last and the inner side of the heel end of the shoe, and actuating mechanism to move said two engaging means in directions perpendicular to one another for forcing the shoe upon the last. 20
20. A shoe mounting machine having, in combination, means to engage the toe of the shoe in the welt crease, a spoon to engage the shoe between its rear end face and the last, and means for actuating the toe engaging means rearwardly and the spoon downwardly relatively to an inverted shoe and in time relation to one another. 25
21. A shoe mounting machine having, in combination, means to engage the toe of the shoe in the welt crease, a spoon to engage the shoe between its rear end face and the last, actuating means for yieldingly pressing the toe engaging means rearwardly and for drawing the spoon downwardly while the pressure is increasing. 30
22. A shoe mounting machine having, in combination, a spoon for application between the rear end of a partially inserted last and its shoe, means for drawing the spoon in the direction to pull the shoe on to the last and means operated automatically for simultaneously pressing the forepart of the shoe rearwardly on the last. 35
23. A shoe mounting machine having, in combination, a spoon for application be-
- tween the rear end of a partially inserted last and its shoe, means for operating the spoon and mechanical means for engaging the toe end face of the shoe to press the shoe rearwardly during the operation of the spoon. 40
24. A shoe mounting machine having, in combination, a spoon for application between the rear end of a partially inserted last and its shoe, means for operating the spoon to draw the heel portion of the shoe on to the last, and means engaging the forepart of the shoe and yieldingly pressing the shoe rearwardly during the operation of the spoon. 45
25. A shoe mounting machine having, in combination, means to engage the heel portion of a shoe to draw it on to a partially inserted last, means to engage the forepart of the shoe and operating mechanism for causing said latter engaging means to force the shoe lengthwise of the last toward the heel during said operation of the heel engaging means. 50
26. A shoe mounting machine having, in combination, means to engage the heel portion of a shoe to draw it on to a partially inserted last, and a concave edged device arranged to engage the toe of the shoe in the welt crease and movable to press the shoe toward the heel of the last to facilitate the application of the heel portion of the shoe to the last. 55
27. A shoe mounting machine having, in combination, means to engage the heel portion of a shoe to draw it on to a partially inserted last, and means arranged to engage the forepart of the shoe bottom and movable rearwardly to press the shoe toward the heel portion of the last. 60
28. A shoe mounting machine having, in combination, means to engage the heel portion of a shoe to draw it on to a partially inserted last, means arranged to engage the forepart of the shoe bottom, and operating devices for causing the bottom engaging means to press the shoe rearwardly while the heel portion of the shoe is being drawn on to the last. 65
29. A shoe mounting machine having, in combination, means for supporting a last partially inserted in a shoe, a device for pressing the shoe rearwardly on the last, a device to draw the shoe over the heel of the last and mechanism for operating the first mentioned device to move the shoe rearwardly on the last while the shoe is being drawn over the heel of the last. 70
30. A shoe mounting machine having, in combination, means for supporting a last partially inserted in a shoe and coöperating devices engaging the bottom and the rear end of the shoe and connected for operation together in the directions, respectively, to force the forepart of the shoe rearwardly. 75

- on the last and the rear part of the shoe downwardly over the heel of the last.
31. A shoe mounting machine having, in combination, means for supporting a last partially inserted in a shoe, a spoon to engage the rear portion of the shoe for drawing it on a last, means for operating the spoon, and means engaging the bottom of the shoe and movable during the operation of the machine to apply rearward pressure to the sole.
32. A shoe mounting machine having, in combination, a spoon for movement between the rear end face of a last partially inserted into a shoe and the inside of the heel of the shoe to draw the shoe on to the last, and power means for reciprocating the spoon, said spoon being constructed and arranged to rise, during its return stroke, with its upper end inclined away from the work.
33. A shoe mounting machine having, in combination, a spoon for movement between the rear end face of a last partially inserted into a shoe and the inside of the heel of the shoe to draw the shoe on to the last, and power means for reciprocating the spoon, said machine having provision for positioning the spoon backwardly out of engagement with the shoe during its upward stroke.
34. A shoe mounting machine having, in combination, a spoon for movement between the rear end face of a last partially inserted into a shoe and the inside of the heel of the shoe to draw the shoe on to the last, and power means for reciprocating the spoon, including yielding spoon raising means adapted to permit arrest of the spoon if it engages the shoe during its rise.
35. A shoe mounting machine having, in combination, means to engage the rear portion of a shoe for forcing it out to the heel of a partially inserted last, means for engaging the forepart of the shoe to press it rearwardly during such operation, and operating mechanism for said two means including provision for applying increasing pressure to the forepart engaging means during the movement of said heel part engaging means.
36. A shoe mounting machine having, in combination, means to engage the rear portion of a shoe for forcing it on to the heel of a partially inserted last, actuating mechanism therefor, a slide yieldingly connected with said actuating mechanism, and forepart engaging devices connected with the slide and arranged to press the shoe rearwardly to facilitate the operation of the heel part engaging means.
37. A shoe mounting machine having, in combination, operating mechanism, a device mounted for positioning movement lengthwise of the shoe and adapted for operative engagement with the shoe, and connected
- means for moving said device into engagement with the shoe and coupling it with its operating mechanism.
38. A shoe mounting machine having, in combination, operating mechanism, a shoe bottom engaging member normally loose from the operating mechanism and mounted for manual actuation into engagement with the shoe, and an eccentric arranged to be set automatically to connect said member to the operating mechanism when the member is engaged with the shoe.
39. A shoe mounting machine having, in combination, operating mechanism, a shoe bottom engaging member, a lever on which said member is carried for movement into and out of contact with the shoe, a toggle for setting said member down upon the shoe, a support for the lever, an eccentric for locking said support to the operating mechanism, and a connection from the toggle to the eccentric for actuating the latter.
40. A shoe mounting machine having, in combination, a shoe bottom engaging member adapted to be clamped down upon the shoe, reciprocating actuating means for pressing said member rearwardly in the shoe mounting operation, and means for automatically releasing said member from the shoe to avoid drag over the shoe during the return stroke of the actuating means.
41. A shoe mounting machine having, in combination, means for supporting a last that is partially inserted into a shoe which has the upper permanently stitched to the sole, and power operated means adapted for engaging the forepart of the said shoe to force the foreportion of the shoe bodily toward the rear end of the last to complete the insertion of the last into said foreportion of the shoe.
42. A shoe mounting machine having, in combination, means for supporting a last that is partially inserted in a shoe, means for engaging the forepart of the shoe and movable rearwardly therewith toward the heel to force the foreportion of the shoe upon the last, and means operating in time relation therewith to draw the heel part of the shoe on to the heel portion of the last.
43. A shoe mounting machine having, in combination, means for supporting a last that is partially inserted in a shoe, toe lasting plates to engage the toe portion of the shoe and press it rearwardly, a friction engaging member for the forepart of the shoe bottom, and means to move said engaging means rearwardly of the last to seat the forepart of the shoe in lasted position on the last.
44. A shoe mounting machine having, in combination, means for supporting a last that is partially inserted in a shoe, lasting plates to engage the toe portion of the shoe, and actuating mechanism therefor comprising

- ing a slide which has a uniform stroke and upon which the lasting plates are adapted for movement longitudinally to position them for the size of shoe to be operated 5 upon.
45. A shoe mounting machine having, in combination, means for supporting a last that is partially inserted in a shoe, lasting plates to engage the toe portion of the shoe, actuating mechanism therefor comprising a slide which has a uniform stroke and upon which the lasting plates are adapted for movement longitudinally to position them for the size of shoe to be operated upon, and 10 means to clamp the wipers on said slide in whatever position they are adjusted.
46. A shoe mounting machine having, in combination, means for supporting a last that is partially inserted in a shoe, lasting plates to engage the toe portion of the shoe, actuating mechanism therefor comprising a slide which has a uniform stroke and upon which the lasting plates are adapted for movement longitudinally to position them 15 for the size of shoe to be operated upon, a shoe bottom engaging member, and means for automatically clamping the wipers on the slide when said member is engaged with the shoe.
- 30 47. A machine of the class described having, in combination, means for supporting a last, a member adapted to be set in engagement with the bottom of the shoe on said last, power mechanism for actuating said member lengthwise of the shoe, and means for automatically loosening said member from the shoe prior to its return stroke.
48. A machine of the class described having, in combination, means for supporting 40 a last, a member adapted to be set in engagement with the bottom of the shoe on said last, means, including a toggle for setting said member in engagement with the shoe bottom, actuating mechanism for reciprocating said member lengthwise of the shoe, and means for breaking the toggle prior to the return stroke of said actuating mechanism to reduce drag on said member during the return stroke.
- 50 49. A machine of the class described having, in combination, means for supporting a last, a shoe bottom engaging member 45, a lever 40 on which said member is supported, and a toggle adapted to be straightened for 55 forcing said member into engagement with a shoe and automatically retaining it in such engagement.
50. A machine of the class described having, in combination, means for supporting a 60 last, a shoe bottom engaging member, a lever on which said member is supported, a toggle adapted to be straightened for forcing said member into engagement with a shoe and automatically retaining it in such engagement, manual means for straighten- 65
- ing the toggle and means for automatically breaking the toggle after said member has performed its function in the operation of the machine.
51. A machine of the class described having, in combination, means for supporting a last, a member 45 for engaging the shoe bottom, a lever 40 upon which said member is pivotally mounted, a support 22 for said lever, means for actuating the lever to force 70 the member toward the shoe, and the arm 21 on the support and having a pin and slot engagement with an extension of the member 45 for turning the member 45 relatively to the lever for the purpose described when 75 said member is raised from the shoe.
52. A machine of the class described having, in combination, means for supporting a last, a member for engaging the bottom of the shoe, a lever upon which said member is mounted, means for actuating said lever to set said member and reversely to free it from the shoe, and means operating automatically to turn said member relatively to the lever into a position remote from the shoe 80 when said member is lifted from the shoe.
53. A machine of the class described having, in combination, means for supporting the last, toe lasting plates, a support therefor, power mechanism for reciprocating said support lengthwise of the shoe for causing said plates to do their work, and a yielding connection between said support and said mechanism to permit the mechanism to complete its stroke after the plates have reached 90 substantially the limit of their movement relatively to the shoe, said yielding connection insuring increased pressure of the lasting plates without necessarily any further advance during the completion of the stroke 95 of the actuating mechanism.
54. A machine of the class described having, in combination, means for supporting the last, toe lasting plates, a support therefor, reciprocating power mechanism for reciprocating said support lengthwise of the shoe for causing said plates to do their work, and means for automatically disconnecting said plates from said actuating mechanism just prior to the return stroke of 100 the actuating mechanism.
55. A machine of the class described having, in combination, means for supporting the last, toe lasting plates, a support therefor, reciprocating power mechanism for reciprocating said support lengthwise of the shoe for causing said plates to do their work, yielding connection between said plates and said mechanism arranged to be compressed 110 during the latter part of the stroke of said mechanism, and means for automatically disconnecting said plates from the mechanism after a certain compression has been 115 effected.
56. A machine of the class described hav- 120

- 130

- ing, in combination, means for supporting the last, toe lasting plates, a support therefor, reciprocating power mechanism for reciprocating said support lengthwise of the shoe for causing said plates to do their work, an eccentric for connecting the plates with the actuating mechanism during the forward stroke, and means for loosening the eccentric to permit non-positive retraction of the lasting plates during the backward stroke of the actuating mechanism.
57. A shoe mounting machine having, in combination, means for operating upon the forepart of a shoe to position it upon a last and coöperating means for operating subsequently upon the heel part of the shoe and connected mechanism for actuating said two means.
58. A shoe mounting machine having, in combination, means for operating on the forepart of a shoe with rearwardly directed movement and pressure to force it toward the heel of a partially inserted last, and means for pulling the heel part of the shoe 25 over the heel end of the last.
59. A shoe mounting machine having, in combination, means for pressing the forepart of a shoe rear wardly upon a partially inserted last, and means for forcing the heel part of the shoe downwardly over the heel end of the last.
60. A shoe mounting machine having, in combination, forepart pressing means, heel part pulling means and operating mechanism for actuating the first mentioned means to start the shoe and then actuating both said means together.
61. A machine of the class described having, in combination, lasting plates, a holder therefor, and means for maintaining said plates normally closed and permitting them to be wedged apart by the introduction of the shoe.
62. A machine of the class described having, in combination, lasting plates, a holder therefor comprising slides on which the plates are pivoted between their ends, and guideways in which the slides are yieldingly held with the plates closed toward each other and which are movable by the shoe to 50 separate the plates.
63. A machine of the class described having, in combination, the lasting plates 36, the slides 35 having rear walls curved about the point of meeting of the lasting plates 55 and to which the plates are pivoted, the holder 32 having guidewalls for said slides similarly curved and the spring 38 arranged to hold the rear ends of the slides separated.
64. A machine of the class described having, in combination, the lasting plates 36 disconnected at their adjacent ends and the plate carriers 35 in which the plates are pivoted between the ends of their acting edges. 65
65. A machine of the class described having, in combination, the lasting plates 36 and the plate carriers 35 formed with slots for the lasting plates symmetrically distanced from the upper and the lower faces of 70 said carriers, said carriers being reversible to present the plates either side up.
